CLAIM

The ornamental design for an automobile, as shown and described.

DESCRIPTION

FIG. 1 is a front and right side perspective view of an automobile showing our new design;

FIG. 2 is a rear and right side perspective view thereof;

FIG. 3 is a front elevational view thereof;

FIG. 4 is a rear elevational view thereof;

FIG. 5 is a right side elevational view thereof, the left side elevational view being a mirror image thereof; and,

FIG. 6 is a top plan view thereof.

The bottom view of the automobile that is not shown forms

no part of the claimed design.
